(57) **CLAIM**

The ornamental design for a tent, as shown and described.

DESCRIPTION

FIG. 1 is a Perspective view of a tent showing my new design;

FIG. 2 is a Front elevational view thereof;

FIG. 3 is a Rear elevational view thereof;

FIG. 4 is a Right side view thereof;

FIG. 5 is a Left side view thereof;

FIG. 6 is a Top plan view thereof;

FIG. 7 is a Bottom plan view thereof;

FIG. 8 is a Perspective view thereof showing the doors opening from front side; and,

FIG. 9 is a Perspective view thereof showing the doors opening from back side.

The broken lines in the drawing depict portions of tent that form no part of the claimed design.
